(57) **CLAIM**

The ornamental design for a stop assembly for a bogie, as
shown and described.

DESCRIPTION

FIG. 1 is a perspective view of a stop assembly for a bogie
showing our new design in an assembled state;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line portion of the figure drawings is included to
show unclaimed subject matter only and forms no part of the
claimed designs. The bracket in the figures is for the purpose
of illustrating the stop assembly for a bogie in an assembled
state and forms no part of the claimed design.
